Des. 203,856

Patented Feb. 22, 1966

203,856

SPOON BOTTOM WIPER

Vito William Florio, 11 General McLean Drive,
Bellport, N.Y.

Filed Mar. 16, 1964, Ser. No. 79,035

Term of patent 14 years

(Cl. D44—29)

FIG. 1

FIG. 2

FIG. 3

FIG. 4

FIG. 1 is a front elevational view of a spoon bottom wiper, showing my new design;

FIG. 2 is a right side elevational view thereof;

FIG. 3 is a bottom plan view thereof;

FIG. 4 is a rear elevational view thereof.

I claim:

The ornamental design for a spoon bottom wiper, as shown.
